KIDNEY GUARD

George C. Reynolds, St. Louis, Mo., assignor to
 National Vulcanized Fibre Co., Wilmington,
 Del., a corporation of Delaware

Application September 19, 1941, Serial No. 411,511

5 Claims. (Cl. 2—2)

The present invention relates to athletic equipment and more particularly to a guard to protect vital organs of the body in the playing of games wherein body contacts play an important part.

In guards used for the protection of the kidneys of a player it is usual to attach the guard to a padded waist band which is strapped about the player's body in such a position as will properly locate the guard over the part to be protected. As an accessory to such a guard it has been proposed to attach thereto a leather or soft fabric strip, sometimes in the form of a tubular member, which is supposed primarily to cushion an impact with the guard, and secondarily to form a lateral projection extending outwardly from the exposed face of the guard and supposed to serve as a support for the belt by which the pants of the player are held in place. However, such attached strips have failed to function because they become saturated with perspiration, sag out of shape, allow the belt to work itself out of place and the pants to drop down around the legs. Furthermore, being merely stitched to the guard, the leather strip affords no reinforcing effect like a corrugation and is often completely torn off to leave the guard without support for the belt.

Some of the objects of the present invention are to provide an improved body guard for use in athletic games, to provide a guard and belt support formed of a strong, tough, resilient and rigid fibre that will function under service conditions; to provide a kidney guard having an integral belt supporting ledge recess; to provide a novel ledge construction for kidney guards which serves to effectively hold the player's pants up while maintaining the guard down in proper protecting position; to provide a guard and belt supporting ledge formed as a molded unitary structure of light, tough, impact resisting material; and to provide other improvements as will hereinafter appear.

In the accompanying drawing Fig. 1 represents an elevation of a kidney guard embodying one form of the present invention, the same being shown attached to a padded waist band of which only a part is shown as illustrative of the assembly; Fig. 2 represents an elevation of the inner face of the guard; Fig. 3 represents a section line 3—3 of Fig. 1; and Fig. 4 represents a plan of the guard.

Referring to the drawing one form of the present invention consists of a guard 10 formed of fibre or other suitable protective material capable of being molded to a required shape and of such

tough resistant quality as to withstand impact with the ground or impact due to collision so that vital parts of the wearer are protected in the playing of football or other body contact games. As shown the guard 10 is relatively thin and of such arcuate configuration as to generally conform to the shape of the human body at or near the waist line.

In elevation the body is bounded by an upwardly and laterally curved edge 11, and a downwardly and laterally curved edge 12, the latter having an inverse curve 13 for snug fit above the hip of the user. The two edges 11 and 12 meet at the front of the guard in a rounded edge 14, which is relatively narrow in width, while at the rear of the guard the edges meet in a rounded edge 15 which is materially wider than the aforesaid edge 14. Thus at the rear, where protection is more or less vital, the body of the guard is of such area as will form a complete shield to receive impacts, while at the front the protecting area is sufficient for the purpose but so reduced as not to interfere with movement of the thigh.

In order to provide means for seating a belt 25 to support the pants of the wearer, the dies by which the guard is molded are so shaped as to force the material under pressure inwardly from the inner face of the body and outwardly from the outer face of the body along the substantially medial portion of the body whereby a belt retaining lip or ledge 16 is formed upon the outer face of the guard body. It should be noted that the outer wall 17 of this lip 16 curves downwardly and inwardly to merge into the face of the guard, while the inner wall 18 inclines downwardly to meet the face of the guard at an angle whereby a linearly disposed recess 20 is provided of such a depth as will snugly receive a belt and prevent its lateral displacement. Thus the outer wall 17 forms a gradually sloping, smooth surface which generally conforms to hip curvature so that the danger of injury incident to abrupt projections is reduced to a minimum. In use the guard 10 is permanently attached to a waist or girdle 21 by sewing it thereto as indicated by the dotted line stitching adjacent the margin of the guard. Usually both a right side and a left side guard are used. The assembly of the guard and waist is such that the ledge 16 assumes a substantially horizontal position and thus becomes a positive support for the waist line of the trousers when the belt is tightened to force the trouser material down into the recess 20.

When the waist with its attached guards 10 is strapped in place on the athlete, the wearer's

pants are pulled up and over the waist until the belt on the pants is above the two guard ledges 16, whereupon the belt is tightened about the guard and pushed down well within the ledge to seat in the recess at the bottom thereof. Since the ledge wall is rigid and self sustaining any tendency of the belt to ride out of the recess or off of the ledge is resisted in a positive manner. Furthermore, since there is a tendency of the waist to ride upwardly the interlock between the ledge and belt prevents such displacement. In other words the two opposed forces (the waist pull upward and the pants pull down) react to maintain a firm lock between the belt and ledge. The dotted lines indicate respectively the waist 21, the pants 22, and the belt 23.

It will now be apparent that a complete unitary guard, for the purpose intended, has been devised wherein a rigid integral sustaining means is provided for coaction with a belt or other article by which a player's pants can be held in place during violent exercise. This also helps to keep the pad down and properly located. While the material of the guard is extremely light and adds little to the weight of the equipment, it is tough and resists impact without bending or breaking. Furthermore, the molded ledge is molded with a smooth curvature which minimizes the projection while forming a relatively deep seat for retaining the cooperating belt and decreases the wear, marking and soiling of the garment.

Having thus described my invention, I claim:

1. As a new article of manufacture for attachment to a waist or girdle, a fibre guard for protecting vital parts of an athlete from impact, said guard being molded with an integral pro-

jecting ledge on the outer face thereof, whereby in operative position said ledge is substantially horizontally disposed to serve as a support for the belt portion of the user's trousers, while said guard lessens body impacts.

2. As a new article of manufacture, a fibre guard for protecting vital parts of an athlete from impact, molded in arcuate shape to conform to body curvature and having an integral ledge projecting from the outer face thereof, said ledge forming a re-entrant longitudinally disposed seat.

3. A kidney guard for athletes, comprising a body of thin fibre shaped to conform to body curvature and having an elongated ledge pressed outwardly therefrom to form a support for trousers when the latter are supported by a belt.

4. A kidney guard for athletes, comprising a body of thin fibre shaped to conform to body curvature, an elongated rigid ledge formed on the outer face of said body having an inner wall inclined with respect to the outer face of said body to form a wedge shaped recess at its junction with said body to receive the belt portion of trousers when the latter are supported by a belt.

5. A kidney guard comprising a molded sheet generally curved in a fore and aft section and generally planar transverse to said section, said sheet having a rounded front edge and a rounded rear edge of greater diameter than said front edge, the upper and lower edges of said sheet being respectively convex and concave to fit snugly over the hip of the wearer, said sheet including an integral fore and aft elongated corrugation forming an upwardly disposed wedge shaped pocket.

GEORGE C. REYNOLDS.
